UNITED STATES PATENT OFFICE.

THOMAS WILSON, OF TORONTO, ONTARIO, CANADA.

DESIGN FOR A TRAY.

47,529.

Specification for Design.

Patented June 29, 1915.

Application filed February 20, 1915. Serial No. 9,734. Term of patent 14 years.

To all whom it may concern:

Be it known that I, THOMAS WILSON, a subject of the King of Great Britain, residing at Toronto, in the Province of Ontario and Dominion of Canada, have invented a new, original, and ornamental Design for Trays, of which the following is a specification, reference being had to the accompanying drawing, forming a part thereof.

The figure is a perspective view of a tray, showing my new design.

I claim:

The ornamental design for a tray, as shown.

THOMAS WILSON.

Witnesses:

A. L. McCORQUODALE,
Edw. S. GREENE.
